UNITED STATES PATENT OFFICE.

PHILIP AVILLA, OF SAN FRANCISCO, CALIFORNIA.

INTERNAL-COMBUSTION ENGINE.

1,312,310.

Specification of Letters Patent. Patented Jan. 16, 1917.

Application filed November 17, 1915. Serial No. 61,322.

To all whom it may concern:

Be it known that I, PHILIP AVILLA, a citizen of the United States, residing at the city and county of San Francisco and State of California, have invented new and useful Improvements in Internal-Combustion Engines, of which the following is a specification.

My invention relates to internal combustion engines, and especially to that class known as two-cycle engines or those in which an explosive charge is drawn in, compressed, ignited and the waste product exhausted at each full reciprocation of the working piston.

It consists of a hollow piston reciprocated within a working cylinder and movable over and exterior to a stationary piston, with ports so disposed and connected that the explosion in the main cylinder acts to compress a charge between the hollow piston and the stationary inner piston, and to transfer it through connecting ports into the main cylinder in readiness for another stroke; the exhaust gases of the previous stroke being substantially discharged at the end of the power stroke of the main piston through a port uncovered at that instant.

It further consists in details of construction which will be more fully explained by reference to the accompanying drawings, in which—

Figure 1 is a longitudinal section, showing the piston in position for an impulse stroke. Fig. 2 is a section showing the piston at the opposite end of the stroke.

As shown, A is the cylinder, here shown as mounted upon a frame or casting B, which forms its support from one end and which also carries the bearings of the crank shaft C.

2 is a hollow piston fitting the cylinder and closed at the outer end. The inner end is open and is connected with a reciprocating device, which, in the present case, consists of a transverse yoke 3 having a sliding box 4 fitting the crank pin 5, so that the revolution of the shaft and crank causes the box 4 to reciprocate from one end to the other of the yoke, which thus reciprocates in the axial line of the piston, and the connection of the piston causes it to move from end to end of its stroke.

Within the hollow piston, and stationary at the inner end of its stroke, is a stationary piston 6, suitably supported from the sta-

tionary frame or equivalent part, so that the head of the hollow cylinder may reciprocate between the outer cylinder and this stationary piston.

7 is an intake passage through the side of the cylinder, and 7^a is a passage through the side of the hollow piston 2 which registers with the passage 7, to admit the explosive mixture, when this piston is at the outer end of its stroke.

8 is a port in the side of the piston, and 9—9^a are ports in the cylinder which may register with the port 8, when the piston is at the inner end of its stroke, to transfer the mixture from within the piston to the cylinder chamber outside of the piston.

The operation will then be as follows: The piston being in position, as shown in Fig. 1, and the crank 5 in position to commence a stroke, a charge of gas is compressed between the cylinder and piston heads, and being ignited by a suitable ignition device, as at 10, the piston will be forced to the opposite end of the cylinder. This compresses a charge previously drawn in through the ports 7—7^a, between the two pistons 2 and 6, until the ports 8 and 9 register, when this charge will be transferred from within the piston to the cylinder chamber. Just previous to this transfer the movement of the piston will have uncovered an exhaust passage 11, in the side of the cylinder, and the residue gases from the explosive impulse stroke against the piston head will escape through this passage. The incoming gas from the interior of the piston is directed toward the head of the cylinder by the baffle plate 12, and thus assists to expel the burned products before the return of the piston has closed the exhaust port. The port 9 having by this time also been closed, by the return movement of the piston, the gas will be further compressed between the piston and the cylinder head for another stroke. During this outward movement of the piston no connecting ports being open a vacuum will occur between the stationary and movable pistons which will be relieved by the inrush of gas when the ports 7 and 7^a are again in register. The next impulse movement of the piston compresses this contained gas in readiness to be transferred to the cylinder when the transfer ports are open, and thus the operation continues.

Having thus described my invention, what I

I claim and desire to secure by Letters Patent is—

1. In an internal combustion engine, a base, a cylinder surmounting the same, a hollow piston operating in the cylinder and having its inner end opened, a rotary crank shaft in the base, a transversely slotted frame having a pair of fixed arms fixedly secured to the piston, the crank of the shaft operating in the slot of the frame, a stationary piston arranged in the hollow piston and provided with fixed extensions connected concentrically to the shaft, said cylinder and hollow piston having ports to admit gas to the interior of the latter at the end of the outward reciprocation, a by-pass to transfer the gas from the hollow piston to the cylinder at the end of the power stroke, and means to ignite the charge thus introduced.
2. In an internal combustion engine of the character described, the combination with the cylinder, of a tubular main piston

closed at the end adjacent to the cylinder head and having outward extensions on its opened end operating in grooves in the cylinder, a fixed interior piston slidably received in the open end of the main piston, a shaft, means connecting the shaft to the piston extensions to reciprocate the main piston, said cylinder and piston having ports to admit gas to the interior of the main piston at the end of its outward reciprocation, a by-pass to transfer the gas from the interior of the piston to the interior of the cylinder at the end of the power stroke, and means to ignite the charge thus introduced.

In testimony whereof I have hereunto set my hand in the presence of two subscribing witnesses.

PHILIP AVILLA.
